DESIGN FOR A BIRD FIGURE

Leoncio Garcia, Youngstown, Ohio

Application April 3, 1945, Serial No. 118,839

Term of patent 14 years

(Cl. D29—23)

To all whom it may concern:

Be it known that I, Leoncio Garcia, a citizen of the United States, residing at Youngstown, in the county of Mahoning and State of Ohio, have invented a new, original, and ornamental Design for a Bird Figure, of which the following is a specification, reference being had to the accompanying drawing, forming a part thereof.

I claim:

The ornamental design for a bird figure, as shown.

LEONCIO GARCIA.
